United States Patent Office

Des. 228,974

Patented Oct. 30, 1973

228,974

SMALL ARTICLE CONTAINER OR THE LIKE

Rose G. Maiuro and Florence Y. Maiuro, both of 2543 S. Broad St., Philadelphia, Pa. 19148

Filed Apr. 12, 1971, Ser. No. 133,480

Term of patent 14 years

Int. Cl. D3—99

U.S. Cl. D87—1 R

FIG. 1

FIG. 2

FIG. 3

FIG. 4

FIG. 5

FIG. 6

FIG. 1 is a side elevational view of a small article container or the like showing our new design;

FIG. 2 is a front elevational view;

FIG. 3 is a bottom plan view on an enlarged scale;

FIG. 4 is a rear elevational view on the same scale as FIG. 2;

FIG. 5 is an enlarged view taken on the line 5—5 of FIG. 1 with the base being omitted for convenience of illustration; and

FIG. 6 is an enlarged view taken on the line 6—6 of FIG. 1 with the base being omitted for convenience of illustration.

We claim:

The ornamental design for a small article container or the like, substantially as shown.
